1 Claim

ABSTRACT OF THE DISCLOSURE

The invention provides an automatic multi-head embroidery machine which comprises a punched control mechanism, transmission means and connecting elements for controlling the movements of the embroidery frames, wherein needle heads are disposed on a carrier between embroidery heads and each individual embroidery head and needle head is disconnectable by a clutch from a common drive shaft and the loopers of the needle heads derive their drive from a neighboring embroidery head through a transmission below the table of the machine.

BACKGROUND OF THE INVENTION

This invention relates to an automatic multi-head embroidery machine intended for general use for the mass production of embroidery work ranging from the smallest pattern to extended embroidered borders up to several meters in length.

Conventional embroidery machines include automatic multiple head machines and table top machines having needle heads attached to a beam extending freely across and above the working table. Both types of machines are controlled by punched cards which control the movement of the embroidery frames with the aid of a Jacquard mechanism, transmission means and frame holders.

Multiple head automatic embroidery machines substantially comprise several embroidery heads resembling sewing machine heads, each constituting a complete self-contained unit, associated with a common drive for the needle bar and the looper system. The embroidery heads are disposed equidistantly or in groups above a machine table; they have common guide means for the embroidery frames driven by a common drive shaft. Owing to the mechanical transmission of the required movements from the Jacquard mechanism to the embroidery frames and the stability required of the transmitting elements in conjunction with minimum weight (to reduce the moving inertial mass) a transverse stay (stiffening stay) is usually provided between each two embroidery heads for transmitting the motion from the punched card control system to the embroidery frames. If the working heads are closely spaced the provision of such a stay following each second or third head may be sufficient.

The embroidery head and the presence of the stay limit the useful length of the field available for embroidery in the longitudinal direction of automatic multiple head machines. The maximum length available for embroidery equals the distance between neighboring heads (needle spacing) less the width of the embroidery head and less the width of the stay. Automatic multi-head embroidery machines cannot therefore be used for embroidery borders which are several meters in length, unless the foundation material that is to be embroidered is repeatedly clamped up afresh or the embroidery frame containing the material is shifted.

It has already been proposed to remove the obstructing stays between the embroidery heads. However, the guid-

2

ance afforded to the frames is not then reliable and the embroidery work is liable to be inaccurate and rough and suitable only for very special purposes. The stays could be omitted if the main connecting elements were particularly rugged and hence heavy, in which case the weight of the moving members would be excessive.

Table top embroidery machines—also known as automatic portal machines—are fundamentally similar to automatic multiple head machines. The principal difference is that the needle heads are mounted fully independently of the associated looper system above the table top on a portal-shaped support and that the movements of the embroidery frame is not therefore obstructed in the region of the table top. However, the necessity of providing multi-needle table top embroidery machines with the above-mentioned stable and expensive portal type structure which cannot be changed once the dimensions have been fixed is a drawback. Automatic portal type embroidery machines are therefore rarely used for automatic embroidery work and only in very specialized fields of production.

In order that the invention may be well understood, the distinction between an embroidery head and a needle head is hereby given. An embroidery head is defined as the embroidery head member which serves as a drive unit for the needle above the table and for the looper below the table. Embroidery heads are shown in the disclosure of British Pat. 801,907. A needle head means that the needle member and the looper are each driven by a separate shaft. An example of this structure is in the disclosure of U.S. Pat. 2,889,792 wherein the needles are driven by shaft 50 and the loopers are driven by shaft 51.

SUMMARY OF THE INVENTION

It is the object of the present invention to eliminate all the shortcomings of the above-described conventional automatic machines and by making simple changes or readjustments to provide an automatic multi-head embroidery machine which can be employed for nearly every conceivable kind of automatic embroidery work.

It is a further object of the present invention to provide an automatic multi-head embroidery machine having an arrangement wherein the embroidery heads and needle heads are alternated on the carrier support. Embroidery machines exclusively provided with embroidery heads as well as embroidery machines exclusively provided with needle heads are well known, as noted by the above cited prior art.

To attain these objects the present invention provides an automatic multi-head embroidery machine comprising a punched card control mechanism, transmission means and connecting elements for controlling the movements of the embroidery frames, wherein needle heads are disposed on a carrier between embroidery heads and each individual embroidery head and needle head is disconnectable by a clutch from a common drive shaft and the loopers of the needle heads derive their drive from a neighboring embroidery head through a transmission below the table of the machine.

BRIEF DESCRIPTION OF THE DRAWING

Several embodiments of the invention will now be described by way of example and with reference to the accompanying drawing in which:

FIG. 1 is a front elevational view of an automatic multi-head embroidery machine comprising six embroidery heads and five needle heads;

FIG. 2 is a top plan view showing the transmission (frame control mechanism) from the Jacquard mechanism to the embroidery frames;

FIG. 3 is an elevational view of embroidery frames for individual patterns;

FIG. 4 is a similar view of embroidery frames for larger patterns;

FIG. 5 is a view similar to FIG. 1, and

FIGS. 6 to 9 illustrate possible combinations of embroidery frames and working fields for embroidering repeats and borders.

DESCRIPTION OF THE PREFERRED EMBODIMENTS

FIGS. 1 and 2 show conventional embroidery heads 1, 3, 5, 7, 9 and 11 which resemble sewing machines and are firmly mounted at equidistant intervals on a machine table 12, all the embroidery heads being driven by a common drive shaft 13. Between each two adjacent embroidery heads 1 and 3, 3 and 5, 5 and 7, 7 and 9, 9 and 11 one needle head 2, 4, 6, 8 and 10 is mounted on a carrier 15. The drive is provided by a motor 16 which also drives a Jacquard machine 17 arranged adjacent the first embroidery head 1. The loopers 18 of the embroidery heads 1, 3, 5, 7, 9 and 11 derive their motion from the shaft 13 as in ordinary sewing machines. However, the separately mounted loopers 19 of the needle heads 2, 4, 6, 8 and 10 are driven below the machine table 12 by a neighboring embroidery head and transmission means 14.

The Jacquard machine 17 which is controlled by a punched card transmits the controlling impulses through a linkage 20, a rear profile rail 21, connecting arm 22 and a front profile rail 23 to the embroidery frames 24 or 24a shown in FIGS. 3 and 4. The embroidery frames for single patterns are mounted individually or in groups on guide rails 25 which are clipped to the front profile rail 23. Border embroidery frames 26 (FIGS. 6 to 9) of different lengths can be easily attached to the same rail and located by catches.

Each selected needle embroiders the same pattern according to the holes in the punched card (Jacquard card). An eleven-head automatic machine will therefore produce eleven identical patterns when one card is worked through. If a more elaborated embroidery is to be produced on the same automatic machine each of the needle heads 2, 4, 6, 8 and 10 may be independently inactivated by individual clutches 27 (FIG. 1), whereby the needle bars are retained in their raised positions and the larger frames inserted. Each of the embroidery heads 3, 5, 7, 9 and 11 can likewise be independently inactivated as desired by individual clutches.

For embroidering borders (repeat embroidery) the foundation material is placed in border embroidery frames 26 of appropriate length and the same repeat pattern is simultaneously produced by several needles (FIGS. 6 to 9). When all the needles are being used the individual sections adjoin or overlap. Assuming that the needle spacing is a the spacing of neighboring embroidery heads is $2a$ (FIG. 5). The maximum length of an embroidery section which in this case is limited by the arm 22 is $2a$ less the width b of the embroidery heads less the diameter c of the arm, less the safety strip d . This provides a utilizable overlapping area between each embroidery section and the neighboring section. The length of the embroidery section a in this example simultaneously determines the length of the principal repeat which naturally permits further subdivision.

The length available for embroidering, that is, the basic measurement involved with respect to the embodiment herein, is determined by the intervals between the needle heads and the embroidery heads. If, for example, in this embodiment, the spacing of two adjacent needles amounts to 22 centimeters, there is a basic measurement

of 242 centimeters, that is, 10 intervals of 22 centimeters each between 11 heads plus half an interval of 11 centimeters at both ends of the embroidering section forming the overlapping area between each embroidering section and the neighboring section, which amounts to a total length available for embroidering of 242 centimeters. Thus, the longest border that can be produced in one operation in the above described example comprises 11 needles times the length of one embroidering section is 242 cms. Since the embroidering and needle heads can be inactivated, the described automatic embroidery machine permits any length of border divisible by the needle spacing to be produced in a correspondingly large frame.

The invention may be embodied in other specific forms without departing from the spirit or essential characteristics thereof. The present embodiments are therefore to be considered in all respects as illustrative and not restrictive, the scope of the invention being indicated by the appended claim rather than by the foregoing description and all changes which come within the meaning and range of equivalency of the claim are therefore intended to be embraced therein.

What is claimed is:

1. An automatic multi-head machine comprising a machine supporting table, a carrier means, a plurality of first needle support means including embroidery heads and arranged in a row spaced at a predetermined distance from each other; a plurality of second needle support means including needle heads positioned between each of said embroidery heads; said first and second needle support means being disposed on said carrier means; a common drive shaft for said embroidery heads extending in a direction of said row and being connected to said embroidery heads; drive means connected to one end of said drive shaft; common frame means for said embroidery and needle heads adapted to carry material to be embroidered and being arranged in the region of said heads; program control means operatively connected with said frame means for effective movement of said frame means in programmed sequence; a clutch means disposed between each of said embroidery and needle heads, with the exception of said first embroidery head, and said drive means whereby each of said heads may be selectively and individually operatively connected or disconnected; transmission means operatively connected to each needle head of said second needle support means, and mounted below said table; loopers associated with each embroidery head of said first needle support means and being driven by said drive shaft; and loopers associated with each needle head of said second needle support means and being driven by a neighboring embroidery head and said transmission means.
